CONTAINER

Hjalmar Kinberg, Ross, Calif., assignor to American Can Company, New York, N. Y., a corporation of New Jersey

Application December 28, 1944, Serial No. 570,161

1 Claim. (Cl. 220—67)

1

The present invention relates to sheet metal containers or cans and has particular reference to a hermetically crimped end seam for a raw unflanged edge body to provide a can which is hermetically tight and which will resist high internal pressures.

An object of the invention is the provision of a can of simple construction which may be manufactured economically and which has an end closure which may be attached to a raw unflanged edge body in a manner that will be hermetic and yet will resist removal or relative displacement under high pressures within the can.

Numerous other objects and advantages of the invention will be apparent as it is better understood from the following description, which, taken in connection with the accompanying drawings, discloses a preferred embodiment thereof.

Referring to the drawing:

Figure 1 is a perspective view of a can embodying the instant invention; and

Figs. 2 and 3 are enlarged vertical sectional views taken substantially along planes indicated by the lines 2—2 and 3—3, in Fig. 1 with Fig. 2 being taken through the side seam of the can, parts being broken away.

As a preferred embodiment of the instant invention the drawing illustrates a can which includes a tubular body 11 having a side wall section 12 (Fig. 3) and a conventional lock and lap side seam 13. Adjacent its end edges, the body wall section 12 is formed with an outwardly extended offset curved shoulder 15 which merges into a larger diameter body wall section 16. This larger body wall section slopes or flares outwardly at a slight angle to the vertical and terminates in a raw edge 17 which is without hem, flange, or curl of any kind.

The opposite ends of the body 11 are closed and sealed with end closures 21. These end closures are each formed with a countersunk central panel 22 which merges into a surrounding inner flange or upright stepped wall section 23. This upright wall section extends below and above the shoulder 15 and tightly engages against the inner surface of the body wall sections 12 and 16 and follows or conforms to the contour of this wall section, hugging the shoulder tightly.

Adjacent the outer edge of the body 11 the inner flange 23 merges into a curved wall section 25 which extends over the raw edge 17 and joins with an outer depending flange 26. The outer flange 26 extends down around the outside of the can above and below the shoulder 15. Together, the inner and the outer flanges set off a cover

2

channel 27 in which is enclosed the raw edge of the body and the shoulder. The channel carries a sealing compound 28 in which the raw edge 17 is embedded, this construction providing a hermetic seal between the closure and the body.

The outer cover flange 26 tightly engages the outer surface of the body wall sections 12 and 16 and follows the contour of the body past and under the shoulder. The flange terminates just below the shoulder and merges into an increased thickness reversely folded hemmed edge having a broad base 31 which preferably is flat on the bottom. The base merges into and terminates in an inner upright flange or edge 32 of the hem which is folded back against the inner surface of the outer flange. This hem extends entirely around the flange, and is interposed between the flange and the can body and tightly engages both.

The hemmed edge 32 extends up along the body wall section 12. The upper end of the hem curves slightly outward, under and against the shoulder 15 and terminates in a raw edge 34 which abuts against the shoulder. One sharp corner of the raw edge is embedded slightly in the shoulder while the other corner is embedded in the outer flange at a locality adjacent the shoulder, as best shown in Fig. 3. At this point in the outer flange, its thickness is reduced along the curve of the shoulder to bring it into tight engagement with the shoulder. Sealing compound in the channel between the inner and outer flanges and in the slight space adjacent the raw edge 34 of the cover hem provides for and insures a hermetic seal between the body and the outer flange at the shoulder.

At the side seam 13 of the container the same construction of end seam is provided as shown in Fig. 3 with the exception that there are two thicknesses of body material instead of one. However, these two layers of material are soldered together during forming of the body and thus function as a single or unitary layer.

With such a construction of end seam any internal pressure in the can tending to displace a closure member 21 is resisted by the raw edge 34 of the hem 32 biting into the shoulder 15 of the body. The pressure is transmitted through the hem endwise or longitudinally and is absorbed by the heavy or thickened base 31 at the line of fold between the hem and the outer flange 26. The slightly curved upper end of the hem tends to direct this pressure inwardly toward the side wall section 12 of the body which thus forms a back stop in resisting displacement of the closure member.

In like manner the embedded raw edge of the hem reacts under pressure against the bend in the outer flange and tends to force this portion of the flange against and into the body shoulder 15. Hence a structurally strong seam is produced which resists displacement of the cover while at the same time insuring a hermetic seal which is simple in construction and economical of manufacture.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof:

I claim:

A sheet metal hermetically sealed container, 20 comprising a tubular body having an outwardly bent offset shoulder adjacent an end thereof, said body adjacent said shoulder terminating in a raw marginal edge, and an end closure for sealing said body, said end closure having spaced inner and outer flanges defining a channel enclosing the said shoulder and raw edge of said body, said closure flanges being crimped tightly against the body along the line of bend of said shoulder with the outer closure flange disposed inwardly there- 30

of, said outer closure flange terminating in a hem folded back on itself between the body and the flange, the inner wall of said hem closely engaging against the outer wall surface of said body, 5 said hem terminating in an inwardly disposed raw edge abutting beneath said shoulder inwardly thereof for resisting removal of the end closure under high internal container pressure, said hem along its line of fold with said outer flange also having a thickened broad base contacting the tubular body opposite said inner closure flange to reinforce the line of fold and to resist longitudinal movement of said hem when the end closure is under internal container pressure.

HJALMAR KINBERG.
